UNITED STATES PATENT OFFICE

ARTHUR HITCHCOCK ORCUTT AND JOHN WILDSMITH SNARRY, OF BIRMINGHAM, ENGLAND, ASSIGNEES TO THE GEAR GRINDING COMPANY LIMITED, OF BIRMINGHAM, ENGLAND

MACHINE FOR GRINDING OR CUTTING TOOTHED GEAR WHEELS OR OTHER ANALOGOUS OBJECTS

Application filed January 16, 1929, Serial No. 332,984, and in Great Britain January 24, 1928.

This invention relates primarily to machines for grinding toothed gear wheels, but is applicable to other kindred machines. Hitherto the work piece has usually been mounted on a horizontal axis, and a rotating grinding wheel has been arranged to reciprocate in a horizontal plane. When dealing with large work pieces, it is convenient to mount the work piece on a vertical axis and 10 arrange the grinding wheel to reciprocate in a vertical plane. This change in the disposition of the parts involves, however, certain difficulties which it is the object of this invention to overcome. Where a high order of 15 precision is required in the work piece, it is necessary intermittently to trim the grinding wheel in order to maintain the accuracy of its form, and when, as is now contemplated, it is required to reciprocate the grinding 20 wheel in a vertical direction, it is convenient to arrange the trimming mechanism to act on the side of the wheel opposite to that which comes into contact with the work piece. Formerly it has been unnecessary to compensate 25 for the reduction of diameter of the grinding wheel resulting from the trimming action, but with the arrangement herein described, some compensating mechanism is necessary. 30 The invention comprises the correlation of the feed mechanism whereby the work piece is advanced towards the grinding wheel in a direction at right angles to the line of reciprocation of the said wheel, and the feed 35 mechanism whereby the trimming tool or tools is or are advanced towards the grinding wheel, by means of mechanism which includes a pair of relatively movable and preferably graduated parts by which an indication 40 is given to the attendant of the movements imparted to the two feed mechanisms. In the three accompanying sheets of explanatory drawings:—

Figure 1 is a side elevation of a toothed 45 wheel grinding machine provided with this invention.

Figures 2 and 3 are respectively sectional end elevation and sectional side elevation showing to a larger scale than Figure 1 mechanisms constructed in accordance with this

invention for adjusting the positions of the work piece and grinding wheel.

In carrying the invention into effect as shown, the lower portion of the bed *a* of the machine is provided with a slide *b* on which 55 is mounted a vertical spindle *c* carrying the work piece *d*. Any convenient mechanism located at *e* is employed for imparting intermittent, angular or indexing movements to the work piece. Alongside the work piece is 60 arranged on the bed of the machine a vertical guide *f* carrying a slide *g* on which is mounted a rotating grinding wheel *h* which can be reciprocated relatively to the work piece. On the frame of the machine adjacent to that side of the grinding wheel opposite the portion which acts on the work piece, are arranged any suitable trimming tools *i*. Only one tool appears in the drawing, but it will be understood that there are 65 a pair of tools situated one behind the other and acting on opposite faces of the grinding wheel. The trimming tools are operated by any suitable means, but these are not shown in the drawing. 70

The feed mechanism which advances the trimming tools towards the grinding wheel is actuated by a hand operated rotatable spindle *j* which is preferably arranged in a vertical position. At its upper end the 80 spindle carries a worm *k* engaging a worm wheel *l* which rotates a screw *m* engaging a nut *n* on the slide *o* carrying the tools *i*. The spindle *j* also carries a worm *p* engaging with a rotatable worm wheel *q* secured to an annular disc *r*, the periphery of which carries an index mark or graduation. On the same axis as the said worm wheel *q* and disc is mounted another marked or graduated disc *s* which is rotated through bevel or other gearing *t* by 85 a vertical spindle *u* which is connected at its lower end through bevel gearing *v* with a shaft *w* which operates a screw and nut feed mechanism (not shown) whereby the slide *b* carrying the work piece can be moved in a horizontal direction on the bed of the machine. The shaft *w* is actuated by hand through worm *x* and wheel *y*. 95

When the attendant by means of the handle *z* imparts a feed movement to the trimming 100

mechanism the graduated disc *r* connected to this mechanism is moved relatively to the adjacent disc *s*, and the graduations on the two discs indicate to the attendant the amount of feed movement which has been given. Such movement corresponds to a reduction in diameter of the grinding wheel, and consequently before the next feed movement is imparted to the work piece a movement must be imparted through the other feed mechanism by manipulation of the handle 2 sufficient to bring the markings on the two discs into the original condition of coincidence. Movement in excess of this is the useful feed movement which is imparted to the work piece, and this is indicated by the disc *s*.

Whilst we have described the application of our invention to a gear wheel grinding machine, it will be apparent that it is applicable to other analogous machines, and subordinate details can be varied to suit different requirements.

Having thus described our invention what we claim as new and desire to secure by Letters Patent is:—

1. In machines for grinding toothed gear wheels or similar objects, the combination comprising a rotary grinding wheel, a reciprocatory slide on which the said wheel is mounted, a work carrying slide movable in a direction at right angles to the direction of motion of the slide carrying the grinding wheel, means for imparting feed movements to the work carrying slide, a trimming tool, a slide carrying the trimming tool, means for imparting feed movements of the slide carrying the trimming tool, and means for correlating the two feed movements, substantially as described.
2. In mechanisms for grinding toothed gear wheels or similar objects, the combination comprising a rotary grinding wheel, a reciprocatory slide on which the said wheel is mounted, a work carrying slide movable in a direction at right angles to the direction of motion of the slide carrying the grinding wheel, a feed mechanism acting on the work carrying slide, a trimming tool, a slide carrying the trimming tool and movable in a direction parallel with the feed motion of the work carrying slide, a feed mechanism acting on the slide carrying the trimming tool, a pair of coaxial rotary indicating members, either or both of which is graduated, and actuating means connecting the said members to the respective feed mechanisms, substantially as described.

In testimony whereof we have signed our names to this specification.

ARTHUR HITCHCOCK ORCUTT.
JOHN WILDSMITH SNARRY.
